SPINDLES FOR TEXTILE MILL USE

Filed May 9, 1945

UNITED STATES PATENT OFFICE

2,447,854

SPINDLE FOR TEXTILE MILL USE

Herbert Gleitz, Euclid, and Charles E. Miller, East Cleveland, Ohio, assignors to The Marquette Metal Products Company, Cleveland, Ohio, a corporation of Ohio

Application May 9, 1945, Serial No. 592,868

6 Claims. (Cl. 57—135)

1

This invention relates to a new and improved spindle blade assembly including a driving whorl. The above indicates the principal objects of the invention.

A specific object is to provide a spindle blade which can be made economically in any desired size or length from readily machinable bar stock in quantity production on machine tools such as automatic screw machines so as to avoid the relatively expensive methods commonly used, as exemplified by centerless grinding, to produce the opposed tapered or reduced diameter portions at respective ends.

Another object is to provide a textile mill spindle blade, different portions of which may be made inexpensively from materials respectively best suited to the service performed by said portions.

A further object is to provide a spindle blade which, although made in sections secured together end to end, is not subject to warping or bending and consequent wobble when in use.

A further object is to provide a whorl for a spindle blade which will be light in construction and capable of being produced at low price in quantity production and in various designs necessary to meet the varied requirements of the textile industry.

Other objects and features of the invention will become apparent from the description of the preferred procedures and constructions illustrated in the drawings, in which

Fig. 1 is a fragmentary longitudinal central sectional assembly view showing one form of textile mill spindle;

Fig. 2 is a side view of a lower portion of a spindle blade formed separately from a companion or complementary section similarly illustrated in Fig. 3;

Fig. 4 is a fragmentary central sectional and elevational view of adjacent portions of the blade made according to Figs. 2 and 3 when the sections are assembled, and

Fig. 5 is a fragmentary central sectional view showing a different manner of connecting two sections comprising a spindle blade and showing also a modified form of whorl.

Referring to Fig. 1 a bolster case 1 is shown provided with a rigid mounting flange or collar 2 adapted to be secured against the usual spindle rail, diagrammatically indicated at 3, as by a nut 4 engaging threads 5 formed on the bolster case. The usual washer is shown at 6. The flange or collar 2 is preferably made separate from the bolster case but rigidly secured thereto so that the

2

bolster case may be formed economically from tube stock. The flange 2 may be made from separate sections 2a and 2b in accordance with the copending application of Herbert Gleitz, Charles E. Miller and Paul I. Thyreen, Serial No. 589,010, filed April 18, 1945 now Patent 2,417,485 issued March 18, 1947. A whorl hook H is mounted by the flange 2 so as to swing over the usual lower flange of the whorl and outwardly from the bolster to clear such whorl flange.

The bolster case has a bolster-bearing-supporting tubular portion 7 extending above the flange 2 and adapted to carry an anti-friction bearing assembly 10 preferably made substantially in accordance with U. S. Patent 2,351,951, issued June 20, 1944 to Herbert Gleitz or according to the application just mentioned. The hollow interior of the bolster case is shouldered as at 11 to support the bearing assembly and below the shoulder 11 is a decreased diameter bore or socket 12 which is closed at the bottom as by a plug 13 secured rigidly into the lower end of the bolster case for example as described in said application.

Resting on the plug 13 and supported for limited lateral floating movement is a footstep bearing assembly including a hollow body 14 which assembly is preferably made substantially as shown in said Gleitz patent. The footstep bearing has a floating key connection with the supporting plug 13 formed as by mutually engaged tongue and slot portions 15 and 16 on the plug and footstep body respectively. The main body of the footstep is resiliently centered in the bore or socket 12 of the bolster case by three or more outwardly spring pressed buttons or caps 17 supported for radial movement in the body 14 and bearing on the inner wall of the bolster case.

The spindle blade 20 shown in Fig. 1 comprises a larger diameter portion 21, which is press or shrink fitted into the hub 22 of the whorl 25, said hub being made, as hereinafter described, as a separate part of the whorl assembly from the belt receiving or barrel portion 23 of the whorl. Usually the largest diameter portion of the blade is connected to the whorl, as is the large diameter portion 21 of the blade as illustrated. The blade is tapered upwardly from the portion 21 or reduced more or less gradually in cross section to facilitate connection of a bobbin or spool to the blade. The taper usually wedgingly fits the axial hole in the bobbin. Below the whorl-connection portion 21 the blade is tapered or reduced in cross section more or less gradually for enabling the blade to make appropriate connections with the bolster and footstep bearings 10 and 14 such as

described above and in any event contained in the bolster case. The taper of the lower end of the blade is also effective for feeding lubricant to the bolster bearing from the lower portions of the oil retaining bore or socket 12 of the bolster case. Oil climbs an upwardly enlarging tapered shaft. Lubricant is preferably introduced into the bolster case through an oil fitting such as illustrated at O in the flange 2. The downward reduction in cross section of the blade also enables the blade assembly to be easily removed from the bolster case at any time and replaced therein. The above characteristics are common in textile spindles.

The blades such as shown are sometimes as much as thirty inches long and the longer the blade the more difficult it is to machine regardless of taper and/or reductions in diameter in opposite directions. The simplest known production method by which to make circular elongated parts is by turning from bar stock on an automatic screw machine but that method so far as we know has not been used to make spindle blades because in a spindle blade which is tapered or reduced in section toward opposite ends from a generally central point only one of the tapers or reduced portions could be formed except by employment of difficult, if not wholly impractical, side cutting operations to form one of the tapers or reductions in one direction. One taper or series of reductions can be formed on a screw machine and if the piece is relatively short that method is probably the least costly. But opposite tapers could not be so formed economically in a screw machine even on a relatively short piece. In any event spindle blades, regardless of length, are usually made each from one piece of bar stock and the necessary tapers and reductions in diameter are obtained by centerless grinding. If such a method has to be used it is apparent that it is no more costly so to form both ends of a spindle blade, each reduced or tapered by the same operation, since both ends can be reduced or tapered at once by the use of appropriately shaped grinding wheels.

The larger diameter portion 21 of the blade is, as shown, part of an upper section 26 of the blade as preferably formed and as shown particularly by Fig. 3. Said upper section is tapered at 27 from a point just above the whorl hub to nearly the upper end of said section where the blade has the usual reduced cylindrical portion 28 adapted to receive as a pilot support the top opening of the bobbin or spool, hereinafter, for convenience, bobbin. A driving connection between the blade and the bobbin (or an adapter for the bobbin) may be formed between the whorl hub and the bobbin or adapter. In Fig. 1 the top end of the whorl hub 22 is cross slotted as at 29 to provide such driving connection to the bobbin. The lower or bearing engaging portion of the blade shown as comprised by the separate blade section 30 of Fig. 2 includes a cylindrical precision finished portion 31 below the whorl hub and extending through the bolster bearing assembly 10 for direct engagement for example by rollers 10' of said assembly. A tapered portion 32 below the cylindrical portion terminates in more steeply tapered portions 33 and 34, which mate with complementary socket portions of the footstep as usual. All the characteristics described above can be greatly modified.

It will be seen from inspection of Fig. 1 that if the blade 20 were one piece, as usually is the case, the oppositely tapered portions 27 and 32

and the further reduced diameter portions 28, 33 and 34 could not all be made on an automatic screw machine, partly because of the difficulty in side cutting of a long section of stock extending from the chuck or collet of the machine tool and partly because the farther the machined piece extends from the supporting chuck or collet, the greater is the tendency for the piece to whip and cause defective cutting. For further illustration, it will be seen that if the blade, assuming it is one piece, is supported in the machine tool at the part which is to become the upper end of the blade and the stock projects from the chuck in the direction of the arrow A, Fig. 1, the tapered surfaces 32, 33 and 34 could in most cases be at least rough formed on the machine but the upper taper 27 and cylindrical reduction 28 could not be so formed at least as a practical matter in high production because side cutting or turning operations are difficult and tend to defeat the primary objectives in using automatic screw machines, i. e. reduction in cost and obtaining high quantity per machine.

By making the blade in sections as indicated by Figs. 2 and 3 and advancing the stock in the direction of the arrows B and C (Figs. 2 and 3, respectively) in forming the respective sections, all of the surfaces can be formed practically to size requiring additionally only finish grinding or light precision finishing operations, e. g. after heat treatment, to relieve stress and/or to harden as in the case of the portions 31, 33 and 34. The section 30 of Fig. 2 when so formed has one side cutting operation to be performed on it, namely the making of a pilot portion 35 of reduced diameter relative to the bearing engaging portion 31, which pilot-forming reduction at 35 can be effected just prior to cutting off of the stock as at 36. The external surfaces of the section 26 of Fig. 3 can all be formed with final finish on a screw machine including the cut-off end 37. Subsequently, the section 27 is suitably mounted in a chuck or collet and the socket 38 for receiving the pilot portion 35 is formed to suitable depth and accurately centered in the large end of the piece. After complete formation of the two sections 26 and 30, and with the pilot portion 35 of the section 30 made of slightly greater diameter than that of the socket 38, the two sections are assembled as by shrink or press fitting into the relationship shown by Fig. 4. Such method of joining the parts and without requiring any further operation, is adequate to preserve alignment of the sections and produce a spindle blade which, for all practical purposes, is the same as the usual single piece blade, but in view of the circumstances already described, it is much less expensive than a single piece blade and particularly if relatively long. Preferably the socket 38 is made sufficiently deep to allow space for insertion of a wafer or ring of brazing material such as a coil of copper wire 40, Fig. 4, which brazing material is later fused by treatment of the assembled blade in an induction furnace, in a fused salt bath at sufficiently high temperature to fuse the brazing metal or in a controlled atmosphere furnace at such temperature in substantially a non-oxidizing atmosphere.

It should be noted at this point that the brazing mentioned herein both for the blade sections and for the whorl, later described, refers to high melting brazing material such as requiring around 2100° F. and higher. Such brazing causes fusion of the connected parts together and the brazing metal penetrates the infinitesimal

mal spaces remaining between the assembled parts when press or shrink fitted together to cause such effective fusion of the mated parts.

If the sections 26 and 30 have been joined by brazing as indicated above then usually the bearing surface engaging portions 31, 33 and 34 require subsequent hardening and precision finish as by grinding. The blade assembly, before attachment of the whorl is heat treated and drawn and then the bearing engaging surfaces are ground or re-finished to final size by grinding as may be required. If, however, the sections are merely shrink or press fitted together at the pilot and socket joint 35, 38 then it will be apparent that the final surfacing accurately to size and finish may have already been effected on the lower section of the blade as at 31, 33 and 34 and on the upper section wherever required. Usually the length and size of the spindle determines which specific method is to be used since a longer and heavier spindle blade requires a more permanent or stronger joint between the sections, because the larger spindles have to carry greater loads.

It should be borne in mind that the bearing engaging portions such as 31, 33 and 34 of the blade should be made extremely hard to resist wear without rendering the stock intermediate the bearing portions, for example the tapered portion 32 of the blade section 30 or 30a, either bendable in service or brittle. The lower blade section in a two section blade such as illustrated may be heat treated in an induction furnace, either before or after assembly with the cooperating blade section, and only the bearing engaging portions 31, 33 and 34 subject to local heating as by spaced coils in the induction furnace to the critical temperature, then quenched at the proper temperature for the particular steel that is used and then drawn to relieve the stress in the steel all in the same operation and without removing the section from the furnace. The lower blade section 30 is advantageously tool steel, for instance .90 to .100 carbon. The steel is heated to, for instance, 1425° C. to get above the critical temperature. It is then quenched to harden it and then the temperature is brought up to around 250° F. to draw the metal. From the drawing temperature the blade can be quenched or cooled slowly as may be desired.

When the blade sections are brazed together as in the preferred pilot and socket construction described, the assembled sections with the brazing material 40 are fed through a non-oxidizing atmosphere furnace which heats the metal to approximately 2025° to 2200° F. and after passing through the heating chamber of the furnace the blade assemblies pass to a cooling chamber which may or may not contain a non-oxidizing atmosphere but which can, without special expense, reduce the temperature of the blade assemblies sufficiently rapidly to avoid annealing or softening of the bearing engaging surface portions 31, 33 and 34. The final finish surfacing for engagement with the bearings can be performed on the blade before the brazing is done. Usually, however, it is advantageous to effect the final finish grinding later.

The whorl construction shown by Figs. 1 and 5 comprises the separate hub-forming and band-engaging parts 22 and 23 previously referred to. The hub portion 22 comprises simply a screw machine formed part, say of low carbon steel, having a reduced diameter portion 43 turned thereon adjacent a shoulder 44. The barrel part 23 is preferably a section of seamless tubing in the form

of a sleeve which may be expanded as at 46 in suitable dies to form an upper band guide and similarly expanded or flanged as at 47, shown slightly cupped, to form the lower band guide and whorl hook engaging flange. The top of the tube is complementary to the turned surface 43 of the hub member 22, that is to say of proper diameter so as to be shrink or press fitted thereover. The bulged surface portion 48 on the sleeve is for the purpose of centering the band and said surface portion, when required or desired, may be formed as by expanding dies simultaneously with formation of the expanded portions 46 and 47 or later. In some spindles no such barrel shaped portion or upper band guide is necessary. Fig. 5 shows at 25a a whorl made in accordance with the above description but wherein the entire band engaging part 23a is cylindrical except for a lower flange 47a which latter can be formed by any suitable flanging or upsetting operation as well known in the metal working art. Note that the shoulder 44 is omitted from the construction according to Fig. 5 which further reduces cost.

The method of making the blade and whorl assembly according to Figs. 1 to 4 is preferred principally for fairly heavy spindle constructions, whereas the arrangement according to Fig. 5 is more adaptable to light weight spindle constructions. The reason for the preference is that when the socket 38 is formed in the upper blade section of a small size blade, the wall which defines the socket is necessarily less rigid than desired in order that the pilot portion 35 of the lower blade section may be made of a size insuring adequate strength. Thus while the heavy hub 22 of the whorl reinforces the light weight wall defining the socket in the upper blade section when the whorl is pressed or shrunk onto the assembled blade, a stronger light weight blade and whorl assembly can be made according to Fig. 5, wherein neither blade section is socketed.

To secure the two parts of the whorl together into a rigid whorl unit a groove is formed as at 49 or 49a in Figs. 1 and 5, respectively, for receiving brazing material preferably cut from brazing wire and formed into a loop or ring. The assembled parts are brazed under sufficient temperature to fuse the brazing material and cause it to flow along the complementary surfaces of the parts in both directions from the groove.

Fig. 5 also shows a modification of the sectional blade arrangement hereinbefore described comprising butt welding of the upper and lower sections of the blade as at 50. The butt welding is done preferably electrically and, after removal of the flash, the bearing engaging surfaces 31a and the tapered surfaces at the bottom portion of the blade (not shown) are all finally finished prior to assembly of the blade into the whorl hub as by press or shrink fitting. The joint, in case of butt welding of two blade sections, as indicated by Fig. 5, is located between the ends of the bore of the whorl hub and that position wherein the joint 50 is telescoped by the hub is preferred regardless of the particular form or type of whorl which may be used, since the whorl thereby cooperates in holding the blade sections in alignment. In very long blades which may be made by more than two welded joints such as 50, both joints may lie outside the whorl hub. The blade such as shown by Fig. 5 cannot effectively be braze-connected to the whorl or the two sections 26a and 30a brazed together in the hub of the whorl because if the brazing heat by removal of stress in the metal should warp the lower end of

the spindle or draw the temper of the bearing surfaces such would render retreatment, either to harden or grind the surfaces 31a, extremely difficult because those surfaces are disposed within in the whorl.

Comparing the procedure of joining the blade parts as by brazing with the procedure indicated by Fig. 5, wherein the sections 26a and 30a are welded together, it should be borne in mind that some radically different materials well adapted to serve, for example as the top section of the blade but not for the bottom section and vice versa, cannot easily or economically be welded. It is difficult to weld stainless stock such as is highly desirable for the upper blade section in order to resist the corrosive effects of water often present in the thread wound on the bobbin, to tool steel such as admirably suited to use for the lower blade section. Brazing of a stainless steel upper section to a lower section of tool steel is a very simple matter and both types of metal mentioned will withstand the necessary brazing heat and ensuing reduction of temperatures as described without deterioration.

We claim:

1. A textile mill spindle blade comprising two metal sections each of decreased diameter toward one end, the opposite end of one of the sections having a socket and the opposite end of the other section occupying the socket, and held thereby through permanent stress in the metal of the wall of the socket.

2. A blade for a textile mill spindle comprising elongated metal parts of circular cross section, one of said parts having a socket and the other of said parts having a projection snugly occupying the socket and joined thereto by fused metal and a shoulder adjacent the projection abutting the adjacent end of the socketed section.

3. A blade for a textile mill spindle comprising two elongated metal parts of circular cross section, one of said parts having an axial socket and the other of said parts having an axially extending reduced diameter portion snugly occupying the socket, the projection being shorter than the depth of the socket whereby to provide space to accommodate brazing material between the sections and within the socket for fusing the two parts together, said projection and socket being fused together by brazing material in said space.

4. A textile spindle blade and whorl assembly comprising two blade forming sections, one having a terminal socket and the other a terminal portion snugly occupying the socket and a whorl having a hub portion with a central through bore, said hub snugly embracing the socketed tubular section portion in permanently strained reinforcing relation to the defining wall of the socket.

5. A textile spindle blade and whorl assembly

comprising two blade forming sections, one having a terminal socket and the other a terminal portion snugly occupying the socket and secured therein by fused metal, and a whorl having a hub portion with a central through bore, said hub snugly embracing the socketed tubular section portion in permanently stressed reinforcing relation to the defining wall of the socket and having a wall of materially greater thickness than said defining wall.

6. A blade and whorl assembly for a textile mill spindle, said assembly comprising a pair of separate ferrous metal blade sections each having a cylindrical portion and a portion tapered in a direction away from said cylindrical portion, the cylindrical portions being permanently integrally connected by fusion of the metal of each section with the metal of the other, and a whorl having a central cylindrical bore telescoping and in 15 strained embracing relationship to both of said cylindrical portions bridging the same at the point where the sections are fused together, thereby 20 cooperating with the fused metal in holding the sections in permanently aligned and connected relationship.
